UNITED STATES PATENT OFFICE.

GEORGE D. SAILER, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A TRANSPARENT GLASS DISH.

58,200.

Specification for Design. Patented June 21, 1921.

Application filed November 8, 1920. Serial No. 422,741. Term of patent 14 years.

To all whom it may concern:

Be it known that I, GEORGE D. SAILER, a citizen of the United States, residing at Jeannette, in the county of Westmoreland, State of Pennsylvania, have invented a new, original, and ornamental Design for a Transparent Glass Dish, of which the following is a specification, reference being had to the accompanying drawing, forming a part thereof.

Figure 1 is a plan view of a transparent glass-dish showing my new design, and Fig. 2 is a cross section of same on the line 2--2, Fig. 1.

The important feature of my design consists in the provision on the bottom of a transparent dish of rings of spaced projections, the said rings being arranged one within the other.

I claim:

The ornamental design for a transparent glass-dish as shown.

GEORGE D. SAILER.
